[57] CLAIM

The ornamental design for a wall mountable radio transceiver for use with a cordless telephone, as shown and described.

DESCRIPTION

FIG. 1 is a top plan view of a wall mountable radio transceiver for use with a cordless telephone showing my new design;

FIG. 2 is a left side elevational view;

FIG. 3 is a front elevational view;

FIG. 4 is a right side elevational view;

FIG. 5 is a bottom plan view; and

FIG. 6 is a rear elevational view.
